UNITED STATES PATENT OFFICE.

EMIL GEORGE HESS AND WILLIAM HESS, OF WEST TORONTO JUNCTION,
CANADA, ASSIGNORS TO ALICE GRACE HESS; OF SAME PLACE.

DESIGN FOR A KNOB OR PULL.

SPECIFICATION forming part of Design No. 21,227, dated December 8, 1891.

Application filed January 22, 1891. Serial No. 378,705. Term of patent 14 years.

To all whom it may concern:

Be it known that we, EMIL GEORGE HESS and WILLIAM HESS, both of the town of West Toronto Junction, in the county of Cork, in the Province of Ontario, Canada, have invented and produced a new and original Design for Knobs or Pulls, of which the following is a specification.

Figure 1 is a face view embodying our design, and Fig. 2 is a perspective view.

The leading feature of our design is a knob or pull having a series of radiating lines or grooves extending from the center over the front face of the knob or pull and along its

sides, these lines or grooves being crossed by other lines or grooves extending concentrically of the front face and circumferentially of the periphery of the knob. The radial lines are shown at *a*, and the lines crossing at *b*.

What we claim is—

The design for a knob or pull herein shown and described.

EMIL GEORGE HESS.
WILLIAM HESS.
